United States Patent Office.

GEORGE W. VENNER, OF CHARLESTOWN, MASSACHUSETTS.

Letters Patent No. 65,314, dated May 28, 1867; antedated May 15, 1867.

IMPROVEMENT IN PHOTOGRAPHIC-CAMERAS.

The Schedule referred to in these Letters Patent and making part of the same.

TO ALL WHOM IT MAY CONCERN:

Be it known that I, GEORGE W. VENNER, of Charlestown, in the county of Middlesex, in the State of Massachusetts, have invented an Improvement in Camera-Boxes; and I do hereby declare that the following is a full and exact description of the same, reference being had to the accompanying drawings, and to the letters of reference marked thereon.

Nature.

The nature of my invention consists in a peculiar apparatus, by means of which the sensitive plate in a camera-box may be moved so as to bring each part of it successively opposite to the perforations in the diaphragm—the diaphragm itself always remaining nearly stationary in relation to the adjusting-board, and being connected with the camera-box by a sliding-frame and a folding screen.

To enable others skilled in the art to make and use my invention, I will proceed to describe its construction and use.

Figure 1 is a perspective view of an ordinary camera-box, A, resting upon an adjusting-board, B C.

Figure 2 is a section in perspective, showing a part of a camera-box, and showing especially my arrangement for exposing the several parts of the sensitive plate successively to the action of light.

Figure 3 is a longitudinal vertical section.

Figure 4 is a plan of the box on its adjusting-board, B. The dotted lines in this drawing represent one of the positions the box takes as it turns on its swivel-pin, K.

Figure 5 is a cross vertical section.

Figure 6 is a diagram showing how the different parts of the sensitive plate are successively exposed to the action of the light.

The camera-box A is connected with the board B by the swivel-pin K, fig. 4. The position of this pin K may be moved at will to the points represented by K' K'' K''', &c. The board B is attached to the board C by means of a hinge and the piece D, or by any suitable mechanical device. The piece E, figs. 1, 3, and 5, is hinged to the lower board C, and serves as a button to hold up the upper board B, as shown in figs. 3 and 5.

From the above description, and the drawings, it will be seen that the box can be turned or swivelled both horizontally around the point K and vertically about the piece D. Upon the sides of the box A I fix two wires or bars, a a', fig. 2. Upon these wires I hang a frame, M, figs. 2, 3, and 4. Attached to the two sides of this frame, and to the side of the box, are two folding screens, figs. 2 and 5. The screens are made of an opaque flexible material, and are used to protect the plate from the action of light. This frame, M, is free to slide sidewise on the wires a a', or, more correctly, the wires are free to slip through the frame as the box itself is moved from one side to another. It can be seen that the frame M moves vertically with the box, but not horizontally, so that any movement of the box upon the board B causes the frame M to approach one side or the other of the box. Affixed to the frame M, in a vertical position, are the two wires b b', fig. 2. Upon these wires slides a second frame, J, figs. 2 and 5. This frame, J, is connected with the lower board C by means of the link H, the roller I, and the caps e e'. The connecting-bar H is connected with the frame J by a small loose-fitting bolt, as shown. It may be seen that the second frame J has a vertical motion in relation to the box, but is nearly stationary in relation to the lower board C. The other parts of the box, and the adjusting-board, are already understood and in common use, and therefore require no particular description.

Having described the construction of my invention, I will illustrate its use. For example, let us suppose that we require to make sixteen pictures on one plate. I put into the frame J a diaphragm perforated, as shown at N', fig. 5. I now adjust the box into what I call the first position, that is, with its rear end down, as shown in fig. 1, and turned to the left, as shown by the dotted lines in fig. 4. The plate is thus exposed, and four impressions, occupying position corresponding to x x x x, fig. 6, are taken; then moving the box to the right, against the pin p', take four more impressions corresponding to y² y² y² y², on the diagram, fig. 6; then raise the rear of the box, and having buttoned it, as shown at fig. 3, four more impressions are taken, corresponding to o³ o³ o³ o³, on the diagram, fig. 6; then swing the box to the left of the pin P, and take four more impressions corresponding to v⁴ v⁴ v⁴ v⁴, on the diagram, fig. 6.

My invention may be applied to any case when it is desirable to make more impressions upon one plate than

there are tubes in the camera. By substituting a single lens for the four, and removing the diaphragm, the camera may be used for all ordinary purposes, when single pictures are desired.

Claims.

What I claim as my invention, and desire to secure by Letters Patent, is—

1. The compound sliding-frames M and J, made substantially as described, and for the purposes set forth.
2. The method of operating the said sliding-frames M and J by means of the bar H, roller I, caps c c', or their mechanical equivalent, and the lower part of the adjusting-board C.
3. The folding screens d d', substantially as described, and for the purpose set forth.

GEORGE W. VENNER.
